UNITED STATES PATENT OFFICE.

FRANK THURBER, OF LOS ANGELES, CALIFORNIA.

LAMP.

Application filed March 25, 1926. Serial No. 97,412.

The present invention relates to an attachment for head lights for vehicles and the principal object is to provide an improved means for correcting errors in lamp bulb filaments with respect to the focal point of a head light reflector.

An object of the invention is the adjustment of incandescent electric lamps to effect proper focus of its filament relative to a reflector without distortion of the reflector or the lamp-holding means.

A further feature of the invention is a ductile or bendable connection, between the body of the reflector and a lamp holder, which connection, by manipulation, may be varied as to shape for the focusing of a lamp filament relative to the reflector without distortion of the reflector body or the lampholder.

The accompanying drawings illustrate the invention.

Fig. 1 is an axial vertical section of a lamp equipped with my invention;

Fig. 2 is a section on line 2—2 of Fig. 1 illustrating the connection of the plate and reflector;

Fig. 3 is a fragmental view of a modification.

In the drawings, 10 indicates the lamp or head light casing of any ordinary construction. For the purpose of deflecting light rays horizontally to the road directly in front of the vehicle, it is necessary that the lamp globe filament be in true alignment with respect to the focal point of the reflector 11.

In the form of the invention illustrated in Figs. 1 and 2, the casing 10 houses the reflector 11, the latter being located with respect to the casing so as to provide an intervening space 12 therebetween. The reflector 11 and lamp casing 12 are formed with registering axial openings 13 and 14 and a sleeve 15 formed with a flange 16 is disposed in the reflector opening 13. A plate 16' of arcuate conformation is formed with opposite end lugs 17 and 18 and the centrally disposed boss 19, which extends within the space 12 between the reflector and casing. A circular opening is formed through the plate and boss and is adapted for the reception of the sleeve 15 and rivets 20 are utilized to secure said plate 16' to the lamp reflector 11.

A tubular member 21 is detachably received within the sleeve 15 and has its outer end projecting through the opening 14 of the

casing. An insulating plug 22 is positioned within the outer end of the tubular member 21 and has secured thereto a contact pin 23 while at its outer end it is secured to the ordinary socket member 24, the latter being connected to the lead wires 25 from the source of electric supply.

An incandescent globe 26 of the ordinary construction and having a filament 27 is arranged in the lamp casing and it is the primary object of the invention to provide means for adjusting the globe in such manner that the filament will be positioned in alignment with the focal point of the reflector.

The globe 26 is formed with a collar 28 which is received within the open end of the tubular member 21 in the usual manner, so that the proper contact is made with the pin 23, and a screw 29 passing through a diagonally disposed opening in the flange 16 of sleeve 15 serves to hold the tubular member 21 in position therewith.

The plate 16' is constructed of some relatively soft metal having ductile properties, so that the same is capable of being bent to provide for the adjustment of the sleeve 15 supporting the lamp globe 26. By virtue of the ductility of plate 16' it is obvious that the lamp supporting elements may be adjusted and held in such adjusted positions to center the filament as aforesaid.

As shown in Fig. 1, the opening 13 through the base of the reflector 11, is of somewhat greater diameter than the external diameter of sleeve 15 in order to provide room for readily bending the concave plate 16' to focus accurately the filament 27. The opening 14 through the base of the casing 10 is likewise larger in diameter than the external diameter of the tubular member 21 so as not to interfere with the bending of the plate 16'. In Fig. 3 I have illustrated a reflector 40 which at its central part in the area defined by the arc, as indicated by the dotted line 41, is weakened to afford ductility in order that the same may be flexed to allow for the adjustment of the sleeve 42 supporting the incandescent lamp globe 43.

It is obvious that I have provided means for adjusting a lamp bulb in a manner to dispose the lamp filament in focal alignment with the head light reflector and have obviated common defects encountered in the use of light globes of the ordinary construction,

wherein the filaments are not in alignment with respect to the lamp socket wherein they are positioned.

I claim:—

- 5 In combination with a reflector having an opening therethrough; a ductile plate secured to the reflector and having an opening registering with the opening in the reflector; a sleeve extended through the opening in said plate; a tubular member seated in said sleeve and adapted to receive an incandescent electric lamp; means carried by said sleeve
- 10

whereby said tubular member may be lengthwise adjustable in the sleeve, said plate being constructed of ductile material whereby said sleeve, said tubular member and the lamp carried thereby may be bodily shifted with respect to the reflector so that the filament of the lamp may have universal focusing with respect to the reflector.

In testimony whereof, I have affixed my signature.

FRANK THURBER.
